UNITED STATES PATENT OFFICE

151,700

DESIGN FOR A HANDLE FOR KITCHEN UTENSILS OR SIMILAR ARTICLES

Walter C. Lueneburg, Evanston, Ill., assignor to
Eko Products Company, Chicago, Ill., a cor-
poration of Illinois

Application April 4, 1947, Serial No. 138,154

Term of patent 14 years

(Cl. D44—29)

To all whom it may concern:

Be it known that I, Walter C. Lueneburg, a citizen of the United States, residing at Evanston, in the county of Cook and State of Illinois, have invented a new, original, and ornamental Design for a Handle for Kitchen Utensils or Similar Articles, of which the following is a specification, reference being had to the accompanying drawing, forming part thereof.

Fig. 1 is a top perspective view of a handle for kitchen utensils or similar articles, showing my new design.

Fig. 2 is a top plan view thereof.

Fig. 3 is a bottom plan view thereof.

Fig. 4 is an end elevational view illustrating the article as it would appear when viewed from the bottom of Fig. 2.

Fig. 5 is a similar view illustrating the article as it would appear when viewed from the top of Fig. 2.

Fig. 6 is a side elevational view thereof.

I claim:

The ornamental design for a handle for kitchen utensils or similar articles, as shown.

WALTER C. LUENEBURG.
